(57) **ABSTRACT**

A floatation system for a marine vessel with a starboard pontoon, a port pontoon, and a center pontoon positioned therebetween. Outer stokes each extending along an outer length between forward and aft ends, each having an outer surface at an outer angle from a horizontal plane and an inner surface at an inner angle from the horizontal plane, and each being coupled to one of the starboard pontoon and the port pontoon. Inner stokes each extending along an inner length between forward and aft ends, each having an outer surface at an outer angle from a horizontal plane and an inner surface at an inner angle from the horizontal plane, and each being coupled to the center pontoon. The outer angles of the inner stokes are greater than the outer angles of the outer stokes and the inner angles of the inner stokes are less than 90°.

**CROSS REFERENCE TO RELATED
APPLICATION**

The present application is a continuation-in-part of U.S. patent application Ser. No. 16/675,989, filed Nov. 6, 2019, the disclosure of which is incorporated herein by reference.

FIELD

The present disclosure generally relates to systems and methods for configuring pontoons and strakes for marine vessels for bounce reduction and control.

BACKGROUND

The following U.S. Patents and Patent Applications provide background information and are incorporated by reference in entirety.

U.S. Pat. No. 9,937,983 discloses a pontoon boat including at least two pontoon tubes, a platform supported on the at least two pontoon tubes, and an occupancy compartment capable of containing at least one occupant, the occupancy compartment having a length, a width, an upper portion extending vertically above the platform that includes a ceiling, and a lower portion extending vertically below the platform and into one of the at least two pontoon tubes, the lower portion including a floor surface for supporting the occupant. An entrance to the occupancy compartment is provided in the upper portion that permits the occupant to enter and exit the occupancy compartment.

SUMMARY

This Summary is provided to introduce a selection of concepts that are further described below in the Detailed Description. This Summary is not intended to identify key or essential features of the claimed subject matter, nor is it intended to be used as an aid in limiting the scope of the claimed subject matter.

One embodiment of the present disclosure generally relates to a floatation system for a marine vessel. The floatation system includes three pontoons each having a nose cone and a cylindrical portion, the cylindrical portions each having a length extending between forward and aft ends. The three pontoons include a starboard pontoon, a port pontoon, and a center pontoon positioned therebetween. Support members are coupled to the three pontoons such that the three pontoons are interposed. Outer strakes each have a tip and an elongated portion, the elongated portions each extending along an outer length between forward and aft ends, each having an outer surface at an outer angle from a horizontal plane and an inner surface at an inner angle from the horizontal plane, and each being coupled to one of the starboard pontoon and the port pontoon. Inner strakes each have a tip and an elongated portion, the elongated portions each extending along an inner length between forward and aft ends, each having an outer surface at an outer angle from a horizontal plane and an inner surface at an inner angle from the horizontal plane, and each being coupled to the center pontoon. The outer angles of the inner strakes are greater than the outer angles of the outer strakes and the inner angles of the inner strakes are less than 90°.

2

Another embodiment generally relates to a floatation system for a marine vessel. The floatation system includes three pontoons each having a nose cone and a cylindrical portion, the cylindrical portions each having a length extending between forward and aft ends. The three pontoons include a starboard pontoon, a port pontoon, and a center pontoon positioned therebetween. Support members are coupled to the three pontoons such that the three pontoons are interposed. Outer strakes each have a tip and an elongated portion, the elongated portions each extending along an outer length between forward and aft ends, each having an outer surface at an outer angle from a horizontal plane and an inner surface at an inner angle from the horizontal plane, and each being coupled to one of the starboard pontoon and the port pontoon. Inner strakes each have a tip and an elongated portion, the elongated portions each extending along an inner length between forward and aft ends, each having an outer surface at an outer angle from a horizontal plane and an inner surface at an inner angle from the horizontal plane, and each being coupled to the center pontoon. The outer angles of the inner strakes are greater than the outer angles of the outer strakes and the inner angles of the inner strakes are less than 90°.

Various other features, objects and advantages of the disclosure will be made apparent from the following description taken together with the drawings.

BRIEF DESCRIPTION OF THE DRAWINGS

The present disclosure is described with reference to the following Figures.

FIG. 1 is a front view of a floatation system for a marine vessel according of the present disclosure;

FIG. 2 is a bottom isometric view of the floatation system from FIG. 1;

FIG. 3 is a rear isometric view of the floatation system of FIG. 1;

FIGS. 4-6 depict bottom views of various configurations of floatation systems similar to that of FIG. 1 according to the present disclosure;

FIG. 7A depicts a front view of one embodiment of a floatation system presently known in the art;

FIG. 7B depicts an embodiment of a floatation system similar to FIG. 7A, but modified according to the present disclosure;

FIG. 8A depicts another embodiment of a floatation system presently known in the art;

FIG. 8B depicts an embodiment of a floatation system similar to FIG. 8A, but modified according to the present disclosure; and

FIGS. 9A-9B depict top views of the embodiment shown in FIGS. 7B and 8B, respectively.

DETAILED DISCLOSURE

Pontoon boats, or marine vessels incorporating pontoons within their floatation system, are generally known vehicles for enjoying time on the water. The present inventors have recently developed new designs in which an upper structure positioned above the pontoons has been moved towards the forward end of the vessel relative to configurations presently known in the art. For example, these upper structures may include a helm, furniture, fences, and/or various accessories

impacting the center of gravity for the vessel overall. However, through experimentation and development, the present inventors have identified that moving the center of gravity forward can create undesired consequences under certain conditions. For example, the present inventors have identified that, when operated at a high speed, vessels having a forward center of gravity may experience handling issues causing an outside pontoon tube to "pop up" during a high speed turn. This creates an uneasy feeling for the pilot of the boat and a general lack of confidence in its handling capabilities. Through further experimentation and development, the present inventors have identified the presently disclosed alternate running surfaces and configuration to eliminate this popping out of the outside tube, and further that improves the operating performance overall, while also reducing material cost.

FIG. 1 depicts a front view of an exemplary floatation system 10 for a pontoon boat 2 according to the present disclosure. The pontoon boat 2 includes an upper structure 6 mounted to a deck 4 that is supported on the water by a floatation system 10. In the example shown in FIGS. 1-3, the floatation system 10 includes three pontoons 20 each having a nose cone 22 and a cylindrical portion 24 extending along a length 29 between a forward end 26 and an aft end 28. The three pontoons 20 may further be defined as a port pontoon 32, center pontoon 34 and starboard pontoon 36. Each of the three pontoons 20 further includes deflectors 21 as is known in the art.

The floatation system 10 further includes support members 12 coupled to each of the three pontoons 20, which hold the pontoons 20 in an interposed manner. The support members 12 may be coupled directly to the pontoons 20, or as presently shown may be coupled via mounting hardware 14. The support members 12 are further configured to be coupled to the deck 4 for coupling the floatation system 10 thereto. As will become apparent, the lengths 29 of the cylindrical portions 24 of the pontoons 20 need not be the same. Likewise, the center depth 35 (FIG. 1) from the bottom of the center pontoon 34 may not be the same as an outer depth 33 corresponding to the port pontoon 32 and starboard pontoon 36.

FIGS. 1-3 further depict the floatation system 10 having outer strokes 40 coupled to one of the port pontoon 32 or the starboard pontoon 36. Each outer stroke has a tip 42 and an elongated portion 44 that extends an outer length 49 between a forward end 46 and an aft end 48. The outer strokes 40 each define a center line 50 and are at an outer stroke angle 52 relative to a vertical access VA (FIG. 1). As such, each outer stroke therefore extends downwardly from the support member 12 an outer stroke depth 54.

In a similar manner, the floatation system 10 further includes inner strokes 60 each coupled to the center pontoon 34 in a manner similar to that previously described for the outer strokes 40. The inner strokes 60 each have a tip 62 and an elongated portion 64 that extends an inner length 69 between a forward end 66 and an aft end 68. Each of the inner strokes 60 defines a center line 70 that extends away from the center pontoon 34 at an inner stroke angle 72 relative to the vertical axis VA. It will be recognized that the vertical axis VA is also perpendicular to the horizontal plane (not numbered). As such, each of the inner strokes 60 extends downwardly from the underside of the support member 12 and inner stroke depth 74.

In the embodiment shown in FIG. 1, the outer stroke angles 52 of the outer strokes 40 are shown to be the same as the inner stroke angles 72 of the inner strokes 60. However, it should be recognized that other configurations

are also anticipated by the present disclosure in which these angles are not the same. In contrast, the center depth 35 from the center pontoon 34 from the support member 12 is shown to be greater than the outer depths 33 corresponding to the port pontoon 32 and the starboard pontoon 36. Likewise, the outer stroke depth 54 corresponding to the outer strokes 40 are shown greater than the inner stroke depth 74 of the inner strokes 60. Alternate embodiments for these features are also anticipated by the present disclosure.

As shown in FIG. 2, the center pontoon 34 is further configured to include an fuel reservoir 80 for containing fuel for a propulsion device to propel the pontoon boat 2 in a manner known in the art. As will be discussed later, the relative volume of the fuel reservoir 80 may vary, depending in part upon the overall size of the floatation system 10, such as the lengths 29 of the pontoons 20.

FIGS. 4-6 depict various embodiments of floatation systems 10 according to present disclosure, and particularly those in which high-speed turning and the avoidance of the pop-out phenomenon previously discussed are greatly improved over systems presently known in the art. Although the same general structures are present across these figures, each includes progressively longer pontoons 20, inner strokes 60, and outer strokes 40. For the sake of clarity, the same structures and measurement points should be interpreted as existing in FIGS. 4-6 without being numerically repeated in each instance. However, actual dimensions and distances may vary from figure to figure, as is shown.

Exemplary dimensions or measurement points between components and landmarks are provided for comparing the embodiments of FIGS. 4-6 relative to each other, as well as relative to systems presently known in the art. A forward pontoon delta 91 is defined as the distance between the forward end 26 of the center pontoon 34 relative to the port pontoon 32 and starboard pontoon 36. Likewise, an aft pontoon delta 93 is defined as the distance between the aft end 28 of the center pontoon 24 and the aft ends 28 of the port pontoon 32 and starboard pontoon 36. Similar measurements are also defined for the outer strokes 40 and inner strokes 60, including a forward stroke delta 95 defined as the distance between the forward end 46 of the outer strokes 40 and the forward end 66 of the inner strokes 60. Likewise, and aft stroke delta 97 is defined as the difference between the aft end 48 of the outer strokes 40 and the aft end 68 of inner stroke 60.

Similar measurements are also defined between the strokes and the pontoons. A forward outer stroke offset 92 is defined as the distance between the forward end 26 of the port pontoon 32 and starboard pontoon 36 and the forward end 46 of the outer strokes 40. A forward inner stroke offset 94 is defined as the distance between the forward end 26 of the center pontoon 34 and the forward end 66 of the inner strokes 60. In a similar manner, an aft outer stroke offset 96 is defined as the distance between the aft ends 28 of the port pontoon 32 and starboard pontoon 36 and the aft end 48 of the outer strokes 40, where as an aft inner stroke offset 98 is defined as the distance between the aft end 28 of the center pontoon 34 and the aft end 68 of the inner strokes 60.

As shown in FIGS. 4-6, in certain embodiments the forward ends 46 of the outer strokes 40 are aft of the forward ends 66 of the inner strokes 60. In further embodiments, the forward ends 46 of the outer strokes 40 and the forward ends 66 of the inner strokes 60 are aft of the forward ends 26 of all three pontoons 20, whereas the aft ends 48 of the outer strokes 40 and the aft ends 68 of the inner strokes 60 are forward of the aft ends 28 of all three pontoons 20. In further embodiments, the forward ends 46 of the outer strokes 40 are

aft of the forward ends **66** of the inner stokes **60**, and the aft end **28** of the center pontoon **34** is after the aft ends **28** of the starboard pontoon **36** and the port pontoon **32**.

Through research and development, the present inventors have identified that the outer lengths **49** of the outer stokes **40** relative to the inner lengths **69** of the inner stokes **60** impact the performance and stability of the floatation system **10** in operation. This may be particularly pronounced during high-speed turns. Accordingly, the presently disclosed systems improve upon this performance by configuring the pontoons and stokes in a manner not previously known in the art. In certain embodiments, the outer length **49** of the outer stokes **40** is between one and three feet longer than the inner length **69** of the inner stokes **60**, and in certain embodiments specifically approximately two feet longer. Additionally, the present inventors have identified particular performance benefits when the floatation system **10** is configured such that the aft ends **48** of the outer stokes **40** are between five and seven feet forward of the aft ends **28** of the starboard pontoon **36** and port pontoon **32**, and the aft ends **68** of the inner stokes **60** are between nine and twelve feet forward of the aft end **28** of the center pontoon **34**. In further embodiments, the inventors have identified particular advantages when the aft ends **48** of the outer stokes **40** are approximately six feet forward of the aft ends **28** of the port pontoon **32** and starboard pontoon **36**, and the aft ends **68** of the inner stokes **60** are approximately ten feet forward of the aft end **28** of the center pontoon **34**.

These exemplary configurations can be shown in comparison of the floatation systems **10** of FIGS. 4-6. In particular, the figures depict a relatively consistent aft stoke delta **97** between the aft ends **48** of outer stokes **40** and the aft ends **68** of the inner stokes **60** regardless of the lengths **29** of the pontoons **20**. The present inventors have identified that it is particularly this configuration, whereby the aft stoke delta **97** is between one and three feet, and in certain embodiments is approximately two feet, provides particular performance enhancements during high-speed turns for pontoons boats **2** having a forward center of gravity relative to pontoon boats **2** presently known in the art. The stoke length difference allows for smoother water flow and prevents water flow from the center pontoon **34** from interfering with the outer stokes **40** when the pontoon boat **2** is in a turn. Through experimentation and development, the present inventors have further identified that the configurations disclosed herein not only improve the ride and handling of the pontoon boats **2**, but also increased top speed and reduced material costs by permitting shorter stokes. In particular, the present inventors were surprised to discover that the preferred configurations described above performed very well irrespective of the lengths **29** of the pontoons **20**, allowing for standardization of stokes across multiple models of pontoon boats **2**. In certain examples, a floatation system **10** according to the present disclosure results in a reduction of up to 32 feet of material for the outer stokes **40** and inner stokes **60** as compared to like-sized pontoon boats having three pontoons presently known in the art. In addition to a reduction in the cost of extruded aluminum, this also reduces the number of welds required per floatation system **10**, providing further savings in time and labor expense.

In addition to the examples provided above and others provided below, the inventors have found the following ranges of values for the distances and angles provided above to be particularly advantageous. Other ranges are also anticipated by the present disclosure, including ranges within $\pm 5\%$, $\pm 10\%$, and $\pm 20\%$ of exemplary nominal values, for

example. Other exemplary ranges include $\pm 5^\circ$, $\pm 10^\circ$, and $\pm 20^\circ$ of exemplary nominal values.

Through further experimentation and development, the inventors have also identified additional problems with marine vessels known in the art, both those including single and dual marine propulsion devices, and particularly in the context of a pontoon-based floatation system 10. Among these, the inventors have identified that there is a problem with "porpoising", which is a phenomenon in which the front of the marine vessel bounces up and down when under way. Porpoising provides for conditions that are difficult to control, which are both unpleasant and unsafe. The inventors have identified that this phenomenon is caused at least in part by water from a center pontoon 34 and the center stokes 60 associated therewith diverting water towards the outer pontoons, particularly the port pontoon 32 and starboard pontoon 36.

Through further experimentation and development, the inventors have identified that this porpoising may be reduced or eliminated through precise selection of the lengths and positions of the outer stokes 40 and inner stokes 60, including the configurations discussed above, along with configuring the outer stokes 40 and inner stokes 60 to have particular shapes, as discussed herein. In certain embodiments, the inventors have identified that by changing the geometry of the inner stokes 60, the water diverted therefrom can be directed so as to not impact the port pontoon 32 and starboard pontoon 36. In certain examples, the water is diverted in a nearly vertical, downward direction, thereby remaining within the general vicinity of the center pontoon 34. The changes in geometry to be discussed herein may be used in conjunction with the relative lengths of the outer stokes 40 and inner stokes 60 already discussed, or as an alternative thereto, to improve the porpoising condition caused by the floatation system 10.

FIG. 7A depicts the general geometry of inner stokes 60 and outer stokes 40 for a floatation system 10 as may be presently known in the art. In the example of FIG. 7A, the length 41 of the outer stokes 40 are positioned at outer stoke angles 52 (see FIG. 1) relative to the port pontoon 32 and starboard pontoon 36 relative to the vertical plane, which as shown is 57°. In the particular example shown, a lower angle 51 relative to the horizontal plane is approximately 14.3°, and likewise an upper angle 53 also relative to the horizontal plane is approximately 54.6° and the length 41 is approximately 5 5/8". Similarly, the inner stokes 60 extend outwardly from the center pontoon 34 by a length 61, which as presently shown is 5 7/8". The inner stokes 60 each have an upper angle 100 relative to the horizontal plane and an inner angle 102 relative to the vertical plane, which are approximately centered about the inner stoke angle 72 and are presently shown to be 51.5° and 78.5°, respectively. A belly pan 103 is also coupled to the center pontoon 34 in a conventional manner.

The embodiment of FIG. 7A corresponds to a "standard" configuration in which the aft ends 28 of the port pontoon 32 and starboard pontoon 36 are perpendicular to the lengths of the pontoons (i.e., angle x is 90°, see FIG. 9A). FIG. 8A

depicts another exemplary floatation system 10 also presently known in the art, this time corresponding to a "joy-stick" configuration in which the aft ends 28 of the port pontoon 32 and starboard 36 are angled forwardly at an angle x that is greater than 90° from an axis parallel to the lengths of the pontoon (see FIG. 9B). In this case, the inner stokes 60 each have upper angles 100 that are 90° relative to the horizontal plane, as well as lower angles 102 that are 90° relative to the vertical plane.

As discussed above, the inventors have identified that substantial porpoising occurs when pontoon boats 2 incorporating the floatation systems 10 of FIG. 7A or 8A. FIGS. 7B and 8B depict exemplary embodiments of floatation systems 10 according to the present disclosure, specifically improving upon the configurations depicted in FIGS. 7A and 7B, respectively. In particular, the inventors have identified that it is advantageous to configure the inner stokes 60 to have a length 61 within the range of 2"-4", and in certain examples particularly 3" (FIG. 7B) and 2 7/8" (FIG. 8B).

Similarly, the other stokes 40 may be configured as provided above, or in certain examples extend a length 41 ranging from 4 1/2" to 7", or in certain cases 5 5/8". Likewise the upper angles 51 and lower angles 5 may be as provided above, or in certain embodiments range from 12° to 16° and from 50° to 60°, respectively. In certain examples, the upper angles 100 and lower angles 102 are specifically 90° and between 55°-65°, respectively, for example.

By designing the inner stokes 60 to have the upper angles 100 and lower angles 102 provided herein, and particularly lower angles 102 that are less than 90° relative the horizontal plane, the inventors have identified that water is diverted from the center pontoons 34 in a manner that does not disrupt the laminar flow of the other pontoons, thus avoiding the dangerous and undesirable effects of porpoising.

This written description uses examples to disclose the invention, including the best mode, and also to enable any person skilled in the art to make and use the invention. Certain terms have been used for brevity, clarity, and understanding. No unnecessary limitations are to be inferred therefrom beyond the requirement of the prior art because such terms are used for descriptive purposes only and are intended to be broadly construed. The patentable scope of the invention is defined by the claims and may include other examples that occur to those skilled in the art. Such other examples are intended to be within the scope of the claims if they have features or structural elements that do not differ from the literal language of the claims, or if they include equivalent features or structural elements with insubstantial differences from the literal languages of the claims.

What is claimed is:

1. A floatation system for a marine vessel, the floatation system comprising:

three pontoons each having a nose cone and a cylindrical portion, the cylindrical portions each having a length extending between forward and aft ends, wherein the three pontoons include a starboard pontoon, a port pontoon, and a center pontoon positioned therebetween;

support members coupled to the three pontoons such that the three pontoons are interposed; outer stokes each having a tip and an elongated portion, the elongated portions each extending along an outer length between forward and aft ends, each having an upper surface at an upper angle from a horizontal plane and a lower surface at a lower angle from the horizontal plane, and each being coupled to one of the starboard pontoon and the port pontoon; and

inner stokes each having a tip and an elongated portion, the elongated portions each extending along an inner length between forward and aft ends, each having an upper surface at an upper angle from a horizontal plane and an inner surface at an inner angle from a vertical plane that is perpendicular to the horizontal plane, and each being coupled to the center pontoon; wherein the upper angles of the inner stokes are greater than the upper angles of the outer stokes and the inner angles of the inner stokes are less than 90°.

2. The floatation system according to claim 1, wherein the upper angles of the inner stokes are between 80° and 100°.

3. The floatation system according to claim 2, wherein the inner angles of the inner stokes are between 50° and 70°.

4. The floatation system according to claim 2, wherein the inner angles of the inner stokes are approximately 60°.

5. The floatation system according to claim 1, wherein the inner angles of the inner stokes are between 50° and 70°.

6. The floatation system according to claim 1, wherein the inner angles of the inner stokes are approximately 60°.

7. The floatation system according to claim 1, wherein the upper angles of the inner stokes are approximately 90°.

8. The floatation system according to claim 6, wherein the lower angles of the outer stokes are between 10° and 18°.

9. The floatation system according to claim 6, wherein the upper angles of the outer stokes are between 50° and 60°.

10. The floatation system according to claim 8, wherein the lower angles of the outer stokes are between 10° and 18°.

11. The floatation system according to claim 6, wherein the lower angles of the outer stokes are approximately 14° and the upper angles of the outer stokes are approximately 55°.

12. The floatation system according to claim 6, wherein the inner angles of the inner stokes are approximately 60°.

13. The floatation system according to claim 11, wherein the lower angles of the outer stokes are approximately 14° and the upper angles of the outer stokes are approximately 55°.

14. The floatation system according to claim 12, wherein the outer stokes each extend away from the one of the starboard pontoon and the port pontoon by a length that is between 4.5 and 7 inches, and wherein the inner stokes each extend away from the center pontoon by a length that is between 1 and 6 inches.

15. The floatation system according to claim 1, where the support members are further configured to support two marine propulsion devices.

16. The floatation system according to claim 1, wherein the aft ends of the outer stokes are aft of the aft ends of the inner stokes.

17. The floatation system according to claim 14, wherein the outer lengths of the outer stokes are between one and three feet longer than the inner lengths of the inner stokes.

18. The floatation system according to claim 1, wherein the forward ends of the outer stokes are aft of the forward ends of the inner stokes, and wherein the aft end of the center pontoon is aft of the aft ends of the starboard and port pontoons.

19. The floatation system according to claim 1, wherein the inner stokes and the outer stokes extend downwardly away from the support structure an inner stoke depth and an outer stoke depth, respectively, and wherein the inner stoke depth is greater than the outer stoke depth.

20. The floatation system according to claim 1, further comprising a belly pan coupled to the center pontoon.

21. A floatation system for a marine vessel, the floatation system comprising:

three pontoons each having a nose cone and a cylindrical portion, the cylindrical portions each having a length extending between forward and aft ends, wherein the three pontoons include a starboard pontoon, a port pontoon, and a center pontoon positioned therebetween;

support members coupled to the three pontoons such that the three pontoons are interposed;

outer stokes each having a tip and an elongated portion, the elongated portions each extending along an outer length between forward and aft ends, each having an upper surface at an upper angle from a horizontal plane and a lower surface at a lower angle from the horizontal plane, and each being coupled to one of the starboard pontoon and the port pontoon; and

inner stokes each having a tip and an elongated portion, the elongated portions each extending along an inner length between forward and aft ends, each having an upper surface at an upper angle between 85° and 95° from a horizontal plane and an inner surface at an inner angle less than 90° from a vertical plane that is perpendicular to the horizontal plane, and each being coupled to the center pontoon;

wherein the aft ends of the outer stokes are aft of the aft ends of the inner stokes;

wherein the forward ends of the outer stokes are aft of the forward ends of the inner stokes, and wherein the aft end of the center pontoon is aft of the aft ends of the starboard and port pontoons; and

wherein the outer lengths of the outer stokes are between one and three feet longer than the inner lengths of the inner stokes.
